UNITED STATES PATENT OFFICE.

CLARENCE V. ROBERTS, OF PHILADELPHIA, PENNSYLVANIA.

DESIGN FOR AN OIL-STOVE.

No. 37,651.

Specification for Design.

Patented Nov. 7, 1905.

Application filed August 23, 1905. Serial No. 275,496. Term of patent 7 years.

To all whom it may concern:

Be it known that I, CLARENCE V. ROBERTS, a citizen of the United States, residing in Philadelphia, Pennsylvania, have invented a new, original, and ornamental Design for Oil-Stoves, of which the following is a specification.

In the accompanying drawings, Figure 1 is a side view of an oil-stove, showing my new design; and Fig. 2 is a front view of the same.

I claim—

The ornamental design for an oil-stove, as shown.

CLARENCE V. ROBERTS.
